ELECTRON DISCHARGE DEVICE

Lester Feinstein, Bellerose, and Mortimer E. Weiss, Flushing, N.Y., assignors, by mesne assignments, to Sylvania Electric Products Inc., Wilmington, Del., a corporation of Delaware

Filed Aug. 30, 1950, Ser. No. 182,368
14 Claims. (Cl. 313—246)

The present invention relates to electron discharge tubes and more particularly to an improved form of construction of such tubes.

An object of the present invention is to simplify the construction of electron discharge devices.

Another object of the present invention is to utilize the element spacers of the amount of an electron discharge device as part of the evacuated envelope of the device.

Another object of the present invention is the provision of a form of construction for electron discharge devices in which there is provided complete peripheral support of the elements which cooperate with the electron stream.

Still another object of the present invention is to increase the structural rigidity of an electron discharge device.

In most conventional vacuum tube constructions with which we are familiar, the grid or grids and anode of the tube may be supported at one or both ends by leads or eyelets which are inserted in mica spacing washers in order to provide a unitary mount assembly. The mount assembly is then secured to a stem or header at one end of the tube. Thus in general, the entire mount may be considered to be supported at one end by the stem or header and at the other end by the mica spacer which may be entirely free of the envelope or may be to some extent supported by contact with the envelope. In order to allow for some variation in envelope dimensions the spacer may be provided with points which are deformed by contact with the envelope wall to provide a snug fit or metal spring members may be secured to the mica for the purpose of contacting the envelope. Due to the inherent fragility of mica, a secure and rugged support for the mount is not thus obtained. Alternate known forms of tube construction may employ disc-like anode and grid elements sealed between sections of glass tubing. However, such construction, in addition to being expensive and difficult to fabricate, does not provide for accurate dimensioning of the space between elements and is not characterized by extreme ruggedness.

Further objects, therefore, of the present invention are to overcome the disadvantages of previously known vacuum tube constructions which are set out above.

The foregoing objects as well as additional objects which may appear in the following description as it proceeds, are attained in accordance with an aspect of the present invention by providing grid and anode structures which are, or form part of, metallic disc-like elements which are supported around their entire periphery by being soldered or brazed to a ceramic ring spacer interposed between the grid and plate discs. The ceramic ring also forms a part of the vacuum enclosure or envelope of the tube.

The present invention employs a ceramic ring rather than glass because ceramics are inherently dimensionally stable under the high temperatures necessary to join the various parts of the tube to make a completed unit. To the side of the grid disc opposite the ceramic spacer ring is welded, brazed or otherwise hermetically secured, a metal eyelet, in the form of a hollow, metallic cylinder having an outturned flange at one end which is secured to the grid disc. The hollow, cylindrical eyelet is hermetically sealed at a point remote from the outturned flange by means of a glass plug secured within the eyelet. A

2

number of lead-in conductors pass through the glass plug and to their inner ends are secured supports for the cathode, whether it be a filamentary cathode or an indirectly heated solid cathode. The cathode support preferably includes mica spacer elements which engage slots in the grid disc and have shoulders which press against the lower side of the grid disc and thus accurately space the cathode from the grid.

The form of our invention described above utilizes the cylindrical shell or eyelet as a means for connecting to the control grid. If desired, an additional ceramic ring may be interposed between the grid disc and the metal shell so as to provide a separate connection for the grid. The shell may then be connected internally to the cathode to form the cathode connection or it may be employed purely as a shield connection and a separate lead through the glass plug employed for the cathode connection. In the form of the invention described above, the metal-to-ceramic seals are made between the directly contacting edges. In some cases a variation in the amount of brazing material between the ceramic ring and the metal discs may unfavorably affect the spacing between the electrodes within the tube. A modification of our invention, therefore, may utilize a ceramic ring which is H-shaped in cross section with the dimension of the height of the H being accurately determined by grinding to a predetermined size. The anode disc and the grid disc have flat portions which lie against the accurately ground ends of the ring and turned over portions or lips which dip into the channels of the H and are sealed therein by brazing material melted into the channels.

The present invention will be more fully understood by reference to the following detailed description which is accompanied by the drawing in which—

35 FIGURE 1 shows in vertical cross section an embodiment of the present invention while

FIGURE 2 shows a vertical cross section of a modified form of the invention and

FIGURE 3 is a vertical section of the form of the invention shown in FIGURE 2 taken along a vertical plane at right angles to the cutting plane of FIGURE 2 while

FIGURE 4 is a horizontal section taken along line 4—4 of FIGURE 2

FIGURE 5 is a horizontal cross section taken along the line 5—5 of FIGURE 2 and

FIGURE 6 is a vertical section similar to FIGURES 1 and 2 of a modified form of the invention.

FIGURE 1 shows an anode disc 10 which may have a central dished-in portion 11 so dimensioned as to fit within 50 the central aperture of a ceramic ring 12. A second disc 14, having a central aperture 15 therein across which grid wires 16 are stretched to form a grid electrode, is dished similarly to anode disc 10 and adapted to be brazed or otherwise secured to the opposite face of ceramic ring

55 12. To the opposite face of grid disc 14 is secured the flange 17 of a hollow, metallic cylinder or eyelet 18, within which is sealed a glass header disc 20, through which pass a number of lead-in conductors 21. The inner ends of lead-in conductors 21 carry, by appropriate fastening means, mica cathode supporting plates 22, 24 which as shown better in FIGURE 3, have, along their upper edges, a pair of notches 25 in which the filamentary cathode wire 26 rests. The mica plate in the space between notches 25 is preferably extended upwardly in

60 the form of a tongue 27 which is so dimensioned in width and length as to tightly fit within notches 28 and 29 at the ends of the grid disc aperture 15 (FIG. 5).

From a consideration of FIGURE 3 it will be seen that 65 the top edges of the mica spacers 22 and 24 rest against the lower face of grid disc 14 so that the grid to the cathode spacing is accurately determined by the depth of

notches 25. A predetermined tension is applied to the filamentary cathode by a tensioning spring 30 which has a hook portion 31 engaged in a bight at the middle of the filament wire 26. The free ends of spring 30 press against the top of the header disc 20 while the looped spring portions intermediate the ends of the spring are carried by an approximately T-shaped support member having the top of the T inserted within the loops of the spring, while the base of the T is secured to the support for the mica spacer 24. The free ends of the filament are preferably connected to the adjacent pair of lead-in conductors 21 at the outer side of mica spacer 22.

In fabricating a tube according to the present invention, a subassembly, including the metal eyelet 18, the header disc 20 and the filament support and spacer assembly is suitably secured on a temporary support which is adapted to be placed within a bell jar which may be evacuated. The grid disc 14, the ceramic ring 12 and the anode disc 10 are positioned on top of rim 17 of eyelet 18 with thin rings of a brazing alloy interposed between adjacent surfaces. The bell jar is then evacuated and the seals are made by heating the assembly therewith by high frequency induction to a brazing temperature. The brazing material for making the seals may include 2% to 5% of titanium metal alloyed with tin, lead, copper, silver or gold, or alloys of these metals. Such brazing materials have a vapor pressure which permits brazing to be successfully carried out within an evacuated space without the metal migrating over the insulating surfaces and degrading the insulation between elements. After the parts have been brazed together and the joints have solidified, air may be released into the bell jar and the bell jar removed in order to release the completed tube for its intended application. The general method of evacuating and sealing a metal envelope tube within a bell jar has previously been described in an application, Serial No. 94,380, filed May 20, 1946, by Mortimer E. Weiss, co-inventor of the present application.

The form of invention which is shown in FIGURE 2 differs from that previously described in that the anode disc 10 has a deep depressed central portion 11' and the grid disc 14 is dished toward the filament 26 rather than away from the filament in order to decrease the inter-electrode spacing as much as possible while at the same time providing an adequate insulating path between elements. Also in this modification the eyelet 18 is provided around the periphery of flange 17 with a turned over edge 33 as an aid in obtaining the required accurately concentric arrangements of the electrodes, as well as providing an exterior channel or gutter into which a brazing alloy may be placed. In this form of construction, anode disc 10, ceramic ring 12 and grid disc 14 may be bonded together as a separate step. We may thus join these parts together with a brazing material which has a comparatively high vapor pressure by making the braze in an atmosphere of hydrogen at sufficient pressure to prevent evaporation of the brazing material. The final seal between the cathode subassembly and grid anode subassembly may be made in a bell jar with a brazing alloy which has a low vapor pressure.

A further modification of the present invention is shown in FIGURE 6, wherein the ceramic ring 42 is H-shaped in cross section, the channels of the H member being metallized or "finned" before assembly. Ring 42 is accurately ground to predetermine the anode to grid spacing. The anode disc in this form of construction includes a down turned rim 44 which dips into the upper channel of the H, while the shell member 48 dips into the lower channel of the H. The spacing of the grid disc 45 from the anode 40 is determined by the accurately ground height of the ring, while the spacing between the grid and cathode is determined as heretofore described. The brazing metal within the annular channels hermetically seals the tube but variations in the amount of brazing

material cannot affect the spacing between the electrodes. Furthermore, the walls of the channels act as baffles to prevent the possibility of any material evaporated from the brazing metal from depositing on the surface of the ceramic, and thus reducing the resistance between the elements of the tube. The brazing material within the lower channel also serves to electrically connect the cylindrical shell member 48 to the grid disc 45. Alternatively, an additional conductor similar to conductors 21 may be provided, passing through header disc 20 and electrically connected to the grid disc 45. In this form of construction, it is preferable to reduce the diameter of grid disc 45 so that there is no possibility of an electrical connection being formed between shield member 48 and the grid disc 45. The shell member 48 then serves primarily only as a casing member, though if electrical considerations warrant, it may be grounded to serve as a shield.

While we have shown and particularly described several modifications of the present invention, it should be distinctly understood that modifications may be made within the scope of the claims. Thus, additional grid elements may be employed by adding the required number of grids and additional ceramic spacing discs, or a ceramic header may be used instead of a glass header. Also, instead of a filamentary cathode, an indirectly heated cathode may be supported from lead-in conductors 21 to lie in close proximity to the grid disc 14.

What is claimed is:

1. An electron discharge device including an anode disc and a grid disc, a ceramic spacer interposed between said discs and hermetically sealed thereto, a tubular metal member having an insulating plug near one end and a number of lead-in wires passing through said plug, a cathode supported within the other end of said tubular member adjacent said grid disc and said tubular member being hermetically sealed to said grid disc, said lead-in wires carrying supports for said cathode and said supports having extensions bearing against said grid disc for spacing said cathode from said grid disc.
2. An electron discharge device including an anode disc and a grid disc, a ceramic spacer interposed between said discs and sealed thereto, a tubular metal member having an insulating plug near one end and a number of lead-in wires passing through said plug, a cathode supported within the other end of said tubular member and said tubular member being hermetically sealed adjacent said spacer to said grid disc, said lead-in wires carrying supports for said cathode and said supports having extensions bearing against said grid disc for spacing said cathode from said grid disc.
3. An electron discharge device including an anode disc and a grid disc, a ceramic spacer ring interposed between said discs, said discs being brazed to said spacer, a tubular member having an insulating closure near one end and a number of lead-in wires passing through said closure, a cathode adjacent said grid disc and supported within the other end of said tubular member, said tubular member being hermetically sealed to said ceramic spacer, said lead-in wires carrying supports for said cathode and said supports having extensions bearing against said grid disc for spacing said cathode from said grid disc.
4. An electron discharge device including an anode disc and a grid disc, a ceramic spacer ring interposed between said discs, a tubular metal member having an insulating plug sealed near one end, a cathode supported within the other end of said tubular member, said anode disc having a turned down rim, said ceramic ring being H-shaped in cross section and said rim extending into one channel of said ring, said tubular member extending into the other channel of said ring said cathode being spaced from said grid by support members carrying said cathode and having extensions bearing against said grid disc.
5. An electron discharge device including an anode disc and a grid disc, a ceramic spacer ring interposed between

said discs, a tubular metal member having an insulating plug sealed near one end, a cathode supported within the other end of said tubular member, said anode disc having a turned down rim, said ceramic ring being H-shaped in cross section and said rim extending into one channel of said ring, said tubular member extending into the other channel of said ring and a sealing material in said channels binding said rim and said tubular member to said ring said cathode being spaced from said grid by support members carrying said cathode and having extensions bearing against said grid disc.

6. An electron discharge device including an anode disc and a grid disc, a ceramic spacer ring interposed between said discs, a tubular metal member having an insulating plug sealed near one end, a cathode supported within the other end of said tubular member and adjacent said grid disc, said anode disc having a turned down rim, said ceramic ring being H-shaped in cross section and said rim being brazed in a channel of said ring, said tubular member being brazed in the other channel of said ring the height of said ring determining the spacing between said anode disc and said grid disc.

7. An electron discharge device including an anode disc and a grid disc, an apertured ceramic spacer ring interposed between said discs, a tubular member having an insulating closure sealed near one end and a number of lead-in wires passing through said closure, a cathode supported within the other end of said tubular member adjacent said grid disc, said anode disc having a turned down rim, said ceramic ring being H-shaped in cross section and said rim being brazed in a channel of said ring, said tubular member being brazed in the other channel of said ring, tongued spacer members secured to some of said lead-in wires, the tongues of said spacer members fitting into apertures in said grid disc and said spacer members carrying said cathode.

8. An electron discharge device including an anode disc and a grid disc, a ceramic spacer ring interposed between said discs, a tubular metal member having an insulating plug sealed near one end, a cathode supported within the other end of said tubular member, said anode disc having a turned down rim, said ceramic ring being H-shaped in cross section and said rim being brazed in a channel of said ring, said tubular member being brazed in the other channel of said ring, tongued spacer members supported within said tubular member, the tongues of said spacer members fitting into notches in said grid disc and said spacer members carrying said cathode.

9. An electron discharge device including an anode disc and a grid disc having a central aperture therein, grid wires stretched across said aperture, a ceramic spacer ring interposed between said discs and brazed thereto, a flanged tubular member having its flange brazed to said grid disc and an insulating plug sealed in said member remote from said flange, a number of wires sealed through said plug, flat insulating cathode supports secured to said wires, and having tongues resting in notches in the aperture in said grid disc and notches in said cathode supports, and a cathode lying in said last mentioned notches.

10. An electron discharge device including an anode disc and a grid disc having a central aperture therein,

grid wires stretched across said aperture, a ceramic spacer ring interposed between said discs and brazed thereto, a flanged tubular member having its flange brazed to said grid disc and an insulating plug sealed in said member remote from said flange, a number of wires sealed through said plug, flat insulating cathode supports secured to said wires and having tongues resting in notches in the aperture in said grid disc and notches in said cathode supports, and a filamentary cathode lying in said last mentioned notches.

11. An electron discharge device including an anode disc and a grid disc having a central aperture therein, grid wires stretched across said aperture, an insulating spacer ring interposed between said discs and sealed thereto, a flanged tubular member having its flange sealed to said grid disc and an insulating plug sealed in said member remote from said flange, a number of wires sealed through said plug, flat insulating cathode supports secured to said wires and having tongues resting in notches in the aperture in said grid disc and notches in said cathode supports, and a cathode lying in said last mentioned notches.

12. An electron discharge device including an anode disc and a grid disc, a ceramic spacer ring interposed between said discs, the thickness of said ring determining the spacing between said anode disc and grid disc and said ring being sealed to said discs by means independent of the thickness of said discs, a tubular member having an insulating closure near one end and a number of lead-in wires passing through said closure, a cathode adjacent said grid disc and said tubular member being hermetically sealed to said spacer, said lead-in wires carrying supports for said cathode.

13. An electron discharge device including an anode disc and a grid disc, a spacer ring interposed between said discs, a tubular metal member having an insulating plug sealed near one end, a cathode supported within the other end of said tubular member, said anode disc having a turned down rim, said ceramic ring being H-shaped in cross section and said rim being sealed in a channel of said ring and flat faces on said discs resting against the top and bottom of said ring to determine the spacing therebetween, said tubular member being sealed in the other channel of said ring.

14. An electron discharge device including an anode disc and an apertured grid disc, a ceramic spacer ring interposed between said discs, a tubular member having an insulating closure sealed near one end and a number of lead-in wires passing through said closure, a cathode supported within the other end of said tubular member adjacent said grid disc and tongued spacer members secured to some of said lead-in wires, the tongues of said spacer members fitting into apertures in said grid disc and said spacer members carrying said cathode.
